J. K. DAVIS,
SHIELD OR COVER FOR HOT AIR FLUES,
APPLICATION FILED OCT. 12, 1917.

1,274,996.

Patented Aug. 6, 1918.

UNITED STATES PATENT OFFICE.

JOSEPHINE K. DAVIS, OF MAYWOOD, ILLINOIS.

SHIELD OR COVER FOR HOT-AIR FLUES.

1,274,996.

Specification of Letters Patent.

Patented Aug. 6, 1918.

Application filed October 12, 1917. Serial No. 196,144.

To all whom it may concern:

Be it known that I, JOSEPHINE K. DAVIS, a citizen of the United States, residing at Maywood, in the county of Cook, State of Illinois, have invented a new and useful 5 Shield or Cover for Hot-Air Flues; and I do hereby declare the following to be a full, clear, and exact description of the invention, such as will enable others skilled in the art to which it appertains to make and use the same.

This invention relates to an improved shield or cover for the outlet end of a hot air flue, and one of the objects of the invention is to provide an improved, simple and efficient device of this kind, which may be manufactured for a small cost and sold at a reasonable profit.

A further object of the invention is to 20 provide a shield or cover to cover the grating of the outlet end of the hot air flue, to prevent dust, when sweeping the room, from entering the flue, and to prevent the smoke from passing out into the room when making the fire in the furnace.

A further object of the invention is to provide improved means for securing the shield or cover to the grate of the outlet end of the flue, and to provide means to 30 insure a tight joint between the grate plate and the cover or shield.

In practical fields the details of construction may necessitate alterations falling within the scope of what is claimed.

The invention comprises further features and combination of parts as hereinafter set forth, shown in the drawings and claimed.

In the drawings:

Figure 1 is a view in perspective of a 40 portion of the floor and a wall of a room, showing the cover or shield as applied to the grate of the outlet of a hot air flue.

Fig. 2 is a sectional view on line 2-2 of Fig. 1.

Fig. 3 is a perspective view of another 45 form of shield or cover as applied to the grate of the outlet end of a flue.

Fig. 4 is a sectional view on line 4-4 of Fig. 3.

Fig. 5 is a perspective view of the shield or cover shown in Figs. 3 and 4, showing the inner face thereof.

Referring more especially to the drawings, 55 1 designates the outlet opening of a hot air flue 2 which may lead from a furnace or the like (not shown), and 3 denotes a rec-

tangular metallic frame fitting said outlet opening. Journalized in bearings of the upper and lower walls of the frame 3 are the upper and lower pintles 4 and 5 of the 60 vertically disposed damper slats or blades 6. The lower pintles 5 are provided with gears 7, and mounted in suitable guides of a pocket 8 below the frame 3 is a rack bar 9. Pivoted at 10 between lugs 11 is a toothed 65 segment 12, which has a handle 13 oscillating in a slot or opening 14 of a flange 15 of the frame 3. This flange overlies the wall surrounding the opening 1 of the flue. It will be seen that by oscillating the handle 70 13, swinging the segment 12, the rack 9 will be reciprocated, which will rotate or rock the gears 7, consequently opening or closing the damper slats 6. When the slats or dampers are closed, they will overlap each 75 other. The frame 3 is provided with transversely and vertically disposed intersecting grate bars 16 and 17, and 18 denotes the improved shield or cover plate, which is designed to engage the outer faces of the grate 80 bars, to prevent smoke and the like from entering the room when making the fire in the furnace, and to prevent dust from entering the flue when cleaning the room. This shield or cover plate is provided with openings 19 and adjoining flanges 20. Screws 21 pass through the openings 19 and are provided with hooked ends 22, adapted to engage the grate bars, as shown in Fig. 2. By setting up on the wing nuts 23 (which 90 are threaded upon the screws 21), the hooked ends may be drawn in close engagement with the grate bars, since the wing nuts act against the flanges 20, thereby holding the shield or cover plate 18 in place. In Figs. 95 3, 4 and 5 the cover plate or shield on its outer face is provided with a bead 24 conforming to the rectangular shape of the shield. The inner face of the cover plate or shield has a groove or recess 25 immediately 100 adjoining and conforming to the rectangular bead. This recess or groove receives a correspondingly shaped packing strip 26, which may be constructed of any suitable material, for instance a composition of rubber and 105 canvas, preferably a composition of asbestos, to engage the flange 15 of the frame 3, to insure a tight joint between said flange and the shield or cover plate. Riveted as at 27 to the inner face of the shield or cover plate 110 are substantially U-shaped fasteners 28, the spring arms of which pass through the open-

2
ing between the vertical and horizontal grate bars. The spring arms of the fasteners are so shaped and bulged, that by springing apart, the bulges engage on the inner part of the grate bars, to hold the cover plate or shield in place, the packing strips 26 insuring a tight joint.

The invention having been set forth what is claimed as new and useful is:—

10. In combination, an outlet opening of a hot air flue, a frame having grate bars mounted in said opening, a cover plate engaging over the grate bars, the inner face of said shield having a pair of U-shaped spring
15 fasteners provided with bulged spring arms passing between the grate bars, to hold the

shield securely adjacent the grate bars, said shield having its outer face provided with a bead conforming to the rectangular shape of the shield, the inner face of the shield immediately adjoining the bead having a recess or groove, and a packing fitting in said groove between the shield and the frame, thereby insuring a tight joint. 20

In testimony whereof I have signed my name to this specification in the presence of two subscribing witnesses.

JOSEPHINE K. DAVIS.
